Primary Examiner — Nicole C Shiflet*Assistant Examiner* — Karen M. Jones(74) *Attorney, Agent, or Firm* — Foley & Lardner LLP(57) **CLAIM**

The ornamental design for a sealer as shown and described.

DESCRIPTION

FIG. 1 is a top, right perspective view of the claimed design; FIG. 2 is a top view of the claimed design of FIG. 1; FIG. 3 is a bottom view of the claimed design of FIG. 1; FIG. 4 is a right side view of the claimed design of FIG. 1; FIG. 5 is a left side view of the claimed design of FIG. 1; FIG. 6 is a rear side view of the claimed design of FIG. 1; and,

FIG. 7 is a front side view of the claimed design of FIG. 1. The ornamental design which is claimed is shown in solid lines in the drawings. The evenly dashed broken lines illustrate portions of the Sealer that form no part of the claimed design. Any shade lines in the drawings show contour and not surface ornamentation.

1 Claim, 4 Drawing Sheets(56)
